AWNNG FOR DOORS, WINDOWS, AND
SIMILAR OPENINGS

Salvador Matheus Zveibil, Sao Paulo, Brazil

Application January 17, 1950, Serial No. 138,955

14 Claims. (Cl. 160—62)

1

This invention relates to a new covering or awning which, in its features and appearance, constitutes a cross between roller awnings and fixed marquees. It is a covering constituted essentially (but not necessarily) of rectangular rigid scales, panels, plates, slats, or sections of thin material stiffened by means of beads, ribs or adequate frames, made of metal or of plastic material. Instead of being rolled in, the panels are retracted substantially without friction, by means of the very practical device later described. Since the pieces of the covering are not subject to friction, the finishing of their surfaces is less subject to scratches and their durability is multiplied in comparison to that of rolled coverings; hence, their movement also becomes easy because the retraction may be done by means of rollers instead of by friction means.

The awning of the present invention, contrarily to the awnings made of canvas, may show fine effects as to shape and color, as well as durability, when made of steel, aluminum, and so on, and may be externally painted, enameled or coated with a durable and attractive protecting material in any of different known manners; on the other hand, contrarily to metallic awnings, this protection is permanent, since the covering is not exposed to any friction liable to cause damage to same.

The awning of the present invention has an external appearance, when distended, of an ample marquee with slightly offset parts, and when retracted, of a narrow marquee or cornice which still offers protection. It has the advantage over the marquee in that the awning may be prefabricated to a large extent, easily assembled and dismantled, and reutilized, which renders it a movable product and an investment of capital, instead of representing an expense to the buyer. It also has the advantage over the marquee of permitting adjustment of light and shadow according to requirements, thanks to its natural movement and to its operating mechanism, to be later described, and which is designed to regulate the inclination or slope of the awning.

The primary object of the invention is to provide an awning structure which may, to a substantial extent, be prefabricated, which is readily operated to different positions, which is easy to manufacture from various materials, and which gives an attractive and pleasing appearance.

The following description covers, beyond the fundamental idea as to the method of fixing the panels of the covering, a method of and means for adjusting the inclination of the awning, and a possible system of control.

The improved awning constituting the subject of the present invention comprises a support made of articulated rods forming parallelograms which

2

cooperate, on top and on the sides with slides on which rest the panels of the covering secured thereto by pivoted claws or hooks and pins. The upper extension of one of the articulated rods nearest to the wall on which the awning is mounted is conveniently pivoted to the upper end of a slide rail along which may move rollers arranged at the lower end of another one of said rods. This same rod is connected, by means of two conveniently articulated rods, to a horizontal shaft movable by a lever, all in such a way that, when the lever is moved in one direction, the above-mentioned rollers move upwards along the rail, thus extending the support; and, when the lever is moved in the other direction, the rollers move down, retracting the support. The rollers are mounted on an end piece attached to a lower rod, the position of which, in relation to the lower rod, may be varied by means of removable pins, thus to increase or reduce the inclination of the awning. Helical springs, the tension of which may be adjusted by means of pins, are inserted in the rails forming the slides, and exert a compensating action to the movement of the awning structure.

The accompanying drawings illustrate an embodiment of the invention.

In the drawings:

Fig. 1 is a perspective view of an awning constructed in accordance with the invention, showing the supporting structure and the panels or slats, the awning being shown partly retracted and mounted on the side of a building;

Fig. 2 is a broken perspective view of the assembled awning, looking from below toward one side, showing the position of the control lever, the awning in this view being shown extended;

Fig. 3 is a vertical sectional view taken on the line 3—3 of Fig. 1 with parts broken away to show interior structure;

Fig. 4 is a detail view partly in section showing the manner of attaching the panels or slats to the supporting slide rails;

Fig. 5 is a broken sectional view taken on the irregular line 5—5 of Fig. 3, showing the structure of the forward part of the slide rail and cooperating rollers; and

Fig. 6 is a broken horizontal sectional view taken on the line 6—6 of Fig. 3 showing the arrangement of the roller unit in the vertical slide.

The awning panels, plates or slats rest on a pair of spaced supports each constituted by two sets of rods 1 and 2, of sufficient mechanical strength and articulated together so as to form parallelograms, as shown in Figs. 1, 2, and 3. Rods 1, which slope in a forward direction, are used in pairs and are shorter than the plain rods 2 which slope backwards. These rods 2 pass between pairs of rods 1, to which they are articu-

lated or pivoted by means of pins 3. The upper end of rod 2 lying nearest to the wall on which the awning is attached is pivoted to the upper end of a vertical rail, channel member, or slide 4, which is conveniently secured to the wall by means of bolts and nuts 5. The lower ends of the pair of rods 1 lying nearest to the wall has holes 6, in order that, by means of clamp 7 (see Figs. 3 and 6) provided with cotter pins, there may be secured, to said end, a channel or U-shaped end piece 8, also having several holes 9, at its free end on which is mounted two rollers 15. These rollers, movable within the vertical channel slide 4, are mounted under a small platform 10 having on its lower part, standards 11 provided with holes 12. In these holes, which correspond with or match the holes 13 of above-mentioned U-shaped piece 8, is inserted the axle 14 of rollers 15, platform 10 becoming thus pivoted to piece 8. After the rollers are inserted into rail 4, their downward movement within same is limited by a pin 16 which extends through the rail. The upward movement of the rollers 15 is opposed by a spring 17 which bears against platform 10 and against a pin 18 similar to pin 16, the position of this pin 18 being variable by using different holes 19 in the slide 4, in order to increase or reduce the tension of spring 17.

A horizontally-extending shaft 20 bears laterally against or extends through holes in the spaced rails 4 above the holes 19. This shaft 20 has a pawl 21 which is engaged by an operating or control lever 22 (Fig. 2). Said shaft is connected, by means of clamp 23 and pivoted rods 24 and 25, to end piece 8 on the lower end of rod 1, in such a way that rotary movement of shaft 20, produced by means of level 22, is transmitted to the rollers 15 which rise or fall along rail 4, thus opening or retracting the awning. To the upper ends of rods 2, a little above their points of articulation to the pairs of rods 1, are secured, by means of pins 26, the longitudinal outwardly-extending rails or slides 27, which, by virtue of the difference in length of rods 1 and 2, become staggered or offset one above the other, as shown in Fig. 3. These slides 27 have on their upper ends, fixed back claws or hooks 28 and on their lower ends pivoted front claws or hooks 29 to which are secured the panels, slats, or plates 32 having corresponding inwardly bent longitudinal edges 32a and 32b, as shown in detail in Fig. 4. These panels, slats, or laminae are secured to the claws as follows: the back edge 32a of the laminae, which is bent upwards and forward, is inserted in fixed hook 28 of the horizontal slide 27 after loosening a pin 31 (Fig. 3) of the pivoted front hook 29. This hook may be raised or pivoted on pin 30 and inserted in the front downwardly-extending hook-shaped edge 32b of the panel as seen in Fig. 4. After this, the panel is pressed down and pin 31 of the hook 29 is again put in position. This system permits an absolutely reliable and rapid attachment of the panels to the supporting structure. The upper panel 34, which is in contact with the wall, is attached to angle brackets 35 by bolts 36, the angle brackets being rigidly secured to the rails 4 by means of the upper bolts 5, as shown in Fig. 3.

The horizontal rods or slides 27 as shown in Fig. 5, having a C-shaped flattened or channel section formed by downwardly and inwardly bent edges 41, rest respectively on and receive rollers 42, the axles 43 of which are mounted on the upper ends of rods 2 which are preferably bent upwards, as shown. The upper or backwardly-

extending portion of the slides 27 are forked or include two spaced bar sections between which the upper end of the rods or bars 2 extend and to which they are pivoted by a pin 26, as shown in the lower portion of Fig. 5. The upper end of each slide, including the upper one, is pivoted in this way, so that the pivot point is above the rods or bars 1 and below the rollers 42. The end of the first rod 2 to which the upper slide 27 is pivoted, is bent toward the wall and pivoted between the sides of the vertical slide 4 by a bolt 33 at a point above the shaft 20, as shown in Fig. 3. In the structure, as shown, each slide 27 is attached to the remaining structure by a pivot pin 26 at its upper portion and rests upon rollers 42 carried at the upper end of one of the rods 2. This device gives the plates 32 of the awning only one possibility of movement, i. e., the plates 32 secured to the horizontal slides can move only in the direction of movement of these slides. Thus the awning will easily withstand the pressure of wind, whether this pressure is exerted from below or from above said plates.

The end of the pantographic arms unit formed by pivoted rods 1 and 2 is constituted by two rods, 37 and 38, Fig. 1, one on each side of the two end rods 2 and which are pivoted to these so as to form greatly extended parallelograms. The upper ends of rods 37 and 38 are pivoted to a rod 39, parallel to end rod 2, the upper end of which, bent upwardly, carries rollers 42 similar to the described rollers 42 carried by rods 2, and which supports the last longitudinal rod or slide 27.

The inclination of the awning is adjustable by means of the structure shown in Fig. 3, by varying the position of piece 8 in respect to the holes 6 in the first pair of rods 1 and the clamping piece 7 in holes 9 of piece 8.

The operation of the awning is readily effected. The operator acting upon level 22 in the appropriate direction impresses a rotation to the shaft 20. When this occurs, rod 25 is raised or lowered and, by means of rod 24, which is pivoted to it, and pulls or pushes the lower end of the first pair of rods 1 and the member 8 provided with the rollers 15, raising or lowering the rollers 15 in the slide 4, thus extending or retracting the pantographic support.

The awning thus far described presents real advantages among which may be underlined the following: control without any toothed gear wheels, which are of slow operation; opening or closing by a single movement of a lever; the lever being removable avoids interference of third parties, permitting at the same time its operation from inside the building, if desired, without the operator having to expose himself to rainy weather.

The pantographic arm of the support is compact and graceful, and presents a gradually increasing strength from the end to the base; assembly is simple and is effected wholly by the use of prefabricated easily fitted parts; the adjustable inclination allows user to correct the amount of light or shadow; stresses are very small, since only rolling friction prevails between the slides and supports.

The invention having thus been described, the following are its claims:

1. In an awning, including a series of individual rigid overlapping panels extending generally angularly to the wall of the building on which the awning is mounted, a support for said panels comprising pivoted rods forming a pantographic system extending outwardly from the wall under

said panels, an outwardly-extending slide rail on said system for each panel and on which such panel is secured, the rear portion of said rail being pivoted to one rod of said pantographic system, the rail resting in sliding engagement on a second rod of said pantographic system holding the forward edge of said panel above the adjacent forward panel, said slide rail extending forwardly from its pivot point over said second rod and over the rear edge of the adjacent forward panel in spaced relation thereto.

2. An awning as claimed in claim 1 including a vertically arranged guide rail secured to the wall at the position of the pantographic system, said pantographic system including rods extending upwardly and outwardly and rods extending downwardly and outwardly with respect to the wall, an outwardly and downwardly extending rod of said system adjacent the guide rail having its upper end pivoted to said guide rail, an upwardly and outwardly extending rod of said pantographic system adjacent said guide rail having its lower end slidably engaging said guide rail, whereby upward movement of said lower end along said guide rail effects the extension of said pantographic system and downward movement of said lower end along said guide rail effects retraction of the pantographic system.

3. An awning as claimed in claim 2, in which the lower end of the upwardly and outwardly extending rod carries a roller means engaging said guide rail, means for limiting the upward and downward movement of said lower end of said rod, and spring means for urging said lower end of said rod in a downward direction.

4. An awning as claimed in claim 3, in which the lower end of the upwardly and outwardly extending rod of the pantographic system includes an adjustable connection for varying the effective length of the rod and for in turn varying the inclination of the awning with respect to the wall on which it is mounted.

5. An awning as claimed in claim 1, including a roller on the upper end of said second rod in rolling engagement with the under side of said slide rail.

6. In an awning structure for attachment to a building wall, including a series of rigid overlapping plates extending outwardly from the wall with their longitudinal edges generally parallel thereto, a support for said overlapping plates comprising a pantographic system having two series of parallel rods pivoted together and supported on the wall under said plates, means for attaching said plates in overlapping relationship to said pantographic system including an outwardly-extending rail for each plate on which such plate is attached, the back end of said rail including an upwardly and forwardly extending hook engaging the upper back portion of the plate attached to said rail, and a downwardly and backwardly extending hook on the forward end of said rail, the forward edge of said plate including a downwardly and backwardly extending flange engaging over the hook on the forward end of said rail.

7. An awning as claimed in claim 6, in which the back edge of said plate includes an upwardly and forwardly extending flange over which the hook on the back end of the rail extends.

8. An awning as claimed in claim 6, in which the hook on the forward end of the rail is adjustably secured thereto, whereby said plate is readily attached to said rail.

9. In an awning structure for attachment to a building wall, including a series of rigid overlapping plates extending outwardly from the wall with their longitudinal edges generally parallel thereto, a support for said overlapping plates comprising a pantographic system having two series of parallel rods pivoted together supported by the wall and extending under said plates, said pantographic system including rods extending upwardly and outwardly and rods extending downwardly and outwardly with respect to the wall, a guide rail secured to the wall at the position of the pantographic system, said rail having a channel-shaped cross-section and arranged with its open side facing away from the wall, an outwardly and downwardly extending rod of said system adjacent the guide rail having its upper end pivoted to said guide rail, an upwardly and outwardly extending rod of said pantographic system adjacent said guide rail having on its lower end a roller means engaging in the channel of said guide rail, whereby upward movement of said roller means along said guide rail effects the extension of said pantographic system and downward movement of said roller means along said guide rail effects retraction of the pantographic system.
10. An awning as claimed in claim 9, including means associated with said guide rail for limiting the extent of the upward and downward movement of the roller means.

11. An awning as claimed in claim 9, including a compression spring mounted in the channel of said guide rail above the roller means and engaging the roller means.

12. An awning as claimed in claim 9, in which the forward edges of the guide rail are bent inwardly to provide an inside edge channel at each edge of the rail, and said roller means comprises a pair of laterally spaced rollers mounted in the guide rails.

13. An awning as claimed in claim 9, including an operating shaft carried by the guide rail at its upper portion and extending generally parallel to and horizontally along the wall of the building, linkage means connecting said operating shaft with the lower portion of the upwardly and outwardly extending rod adjacent to said guide rail, whereby rotation of said shaft on its axis effects upward and downward movement of the lower portion of the rod to which it is connected and extension and retraction respectively of the awning.

14. An awning as claimed in claim 1, in which the portion of the slide rail resting on said second rod includes downwardly and inwardly-extending sides, a pair of rollers carried on the end of said second rod and fitting within said sides of the rail, the inwardly-extending portions of the sides projecting under the respective rollers of the pair.
